UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A HANDLE FOR SPOONS, FORKS, OR SIMILAR ARTICLES.

SPECIFICATION forming part of Design No. 29,120, dated August 2, 1898.

Application filed July 11, 1898. Serial No. 685,707. Term of patent 7 years.

To all whom it may concern:

Be it known that I, HENRY L. WALLACE, of Wallingford, in the county of New Haven and State of Connecticut, have invented a new Design for a Handle for Spoons, Forks, or Similar Articles; and I do hereby declare the following, when taken in connection with the accompanying drawing and the letters of reference marked thereon, to be a full, clear, and exact description of the same, and which said drawing constitutes part of this specification, and represents a face view of a handle embodying my design.

This invention relates to a design for the handle of a spoon, fork, or similar article of table-service; and the design consists in the ornamentation of the handle, as herein-after described, and shown in the accompanying illustration.

As herein shown, the handle expands slightly a little above its juncture with the lower end, then contracts, again gradually

expanding toward the upper end, where it is ornamented by a spray of roses A, starting from a central rose B and extending down 25 for a short distance upon either side of the handle and inclosing a plain panel C. Upon the slight expansion near the lower end of the spoon is a spray of roses D, extending up onto the plain panel C and downward toward the lower end of the handle, all as shown in the accompanying illustration.

I claim—

The design for a handle for spoons, forks and similar articles, as herein shown and described.

In testimony whereof I have signed this specification in the presence of two subscribing witnesses.

HENRY L. WALLACE.
